UNITED STATES PATENT OFFICE.

EMERICK B. CRAWFORD, OF NEW HAVEN, CONNECTICUT, ASSIGNOR TO OVEN EQUIPMENT & MANUFACTURING COMPANY, OF NEW HAVEN, CONNECTICUT.

EXTERNALLY-INSULATED OVEN.

Application filed May 11, 1926. Serial No. 108,443.

Fig. 1 is a view in side elevation of an oven embodying my invention, the transverse divisions of its sectional metal lining being schematically indicated by broken lines.

5 Fig. 2 is a broken view in side elevation with a portion of the insulating envelope broken away.

Fig. 3 is a broken view in transverse section on the line 3—3 of Fig. 2.

10 Fig. 4 is a broken detail view in vertical section through one of the yielding vapor-tight joints in the top of the lining on the line 4—4 of Fig. 3, with the insulation omitted.

Fig. 5 is a corresponding view in horizontal 15 section of one of the vapor-tight joints in one of the side-walls of the lining on the line 5—5 of Fig. 2.

Fig. 6 is a broken detail sectional view on an enlarged scale on the line 6—6 of Fig. 2.

20 Fig. 7 is a sectional view showing another way of joining the plates of the lining-units, with capacity for expansion and contraction.

Fig. 8 is a broken face view thereof.

This invention relates to an improvement 25 in oven-structures of the type used for large-scale baking operations in various industries. Such ovens are designed for the baking of food-stuffs, japanned and painted articles and foundry cores, and for kindred processes. During any of the processes named above, water-vapor, fumes, or smoke are given off in considerable amounts. These by-products of baking I shall, for convenience, hereafter speak of broadly as "vapors," by 30 which I wish to include any of the emanations of any of the substances or articles subjected to the baking action of the oven. In any case, it is undesirable to have such vapor, fumes, or smoke escape from 35 the oven-chamber at any points except through such controlled openings as are designed for the purpose. The escape of vapor from the oven-chamber into the insulated wall of the oven, for example, will considerably 40 reduce the efficiency of the insulation and cause its disintegration. In some baking processes and particularly in the case of most food-stuffs, it is very desirable to retain water-vapor in the oven-chamber because its 45 presence is beneficial to the product. Fumes or smoke, if allowed to escape from the oven-chamber into the insulation, will not only form a source of heat loss but also many times seep through the insulation and pollute 50 the air surrounding the oven. The converse

of the conditions discussed above is likewise usually undesirable, namely, the leakage from without of moisture, or of finely-divided particles of insulation into the baking-chamber.

60 The object of my invention is to overcome the objections above recited, and others of a kindred nature, by producing a vapor-tight oven-lining with provision for the localized expansion and contraction of its lining, obviating injury to its insulation.

A further object of this invention is to produce an oven-structure, over and around which unbroken and, therefor, highly-efficient heat-insulation material may be applied in any convenient manner, said oven-structure to provide a tight baking-chamber 70 that will prevent the leakage through the metal lining thereof of water-vapor, fumes, or smoke out of the baking-chamber and of 75 moisture or dust into the baking-chamber.

A still further object of this invention is to provide an oven-structure, having the characteristics with regard to prevention of leakage through the baking-chamber walls and 80 with regard to taking care of expansion and contraction as stated above, which will combine low thermal capacity with the mechanical strength necessary to form a suitable retaining-wall for the heat insulation applied 85 to the oven-chamber, without requiring stays, spacers, or formed and folded metal penetrating through this insulation.

With these objects in view, my invention 90 consists in an externally-insulated oven having a metal lining transversely divided to form lining-units sealed together by yielding vapor-tight joints, whereby the contraction and expansion of any one unit does not effect its neighbor.

95 My invention further consists in an externally-insulated oven characterized as above and having certain other details of construction as will be hereinafter described and particularly pointed out in the claims.

100 In carrying out my invention, as herein shown, I erect a linear series of inverted U-shaped frames, each consisting, as shown, of two vertical channel-irons 15 and a transverse I-beam 16, secured to their upper ends 105 by angle-plate 17 and bolts 18, on a suitable concrete foundation 19 upon which the lower ends of the channel-irons rest. I do not, however, limit myself to the use of such channel-irons and I-beams for the frames of 110

the oven. The said frames, however made, are regularly spaced apart upon such a foundation; their number will depend upon the desired length of the oven. These frames 5 support transverse lining-units, each consisting, as shown, of a top-plate 20 and two complementary side-plates 21, the said units being sealed together by yielding vapor-tight joints, so that each unit is free to contract 10 and expand without disturbing its neighbor or the heavy insulation 22 placed over the long oven-lining structure, which is made up of such units. The insulation 22 may be of any approved material and mode of applica- 15

For the purpose of sealing the several lining-units together, so as to provide yielding vapor-tight joints between them, and attaching them to the said frames, I employ for 20 each of such joints two packing-strips 23 of resilient packing material, respectively placed upon the outer surface of the edge of each top-plate 20, as shown in Fig. 4. Each pair of these transversely-arranged parallel strips 23 of packing material has imposed 25 upon it a batten-strip 24 perforated for the reception of a series of bolts 25 which pass between the edges of the said plates and through a series of corresponding perforations in the I-beams 16, whereby the adjacent edges of the top-plates 21 are clamped 30 between the I-beams 16 and the packing-strips 23, and yielding vapor-tight joints formed between the adjacent edges of the top-plates, the slippage of the plates in the 35 joints so formed providing for the expansion and contraction of the individual plates.

Similarly and for the same purpose, the 40 edges of the side-plates 20 are spaced apart and have bearing upon the outer faces of the channel-irons 15 of the frames. Upon the outer faces of their edges I arrange parallel strips of resilient packing material 45 26, upon each pair of which I impose a batten-strip 27, which is furnished with a series of perforations for the passage of a series of clamping-bolts 28 passing between the edges of the said side-plates and also passing 50 through a corresponding series of holes in the channel-irons 15, whereby yielding vapor-tight joints are formed between the side-plates without interfering with their slippage in such joints for contraction and 55 expansion.

The several transverse lining-units are thus sealed together by yielding vapor-tight joints and supported by the said frames which, as shown, though not necessarily, enter 60 into the construction of the yielding vapor-tight joints by which the several transverse lining-units are sealed together.

It will thus be seen that though supported by the said frames, the several transverse lining-units are permitted to individu-

ally expand and contract without any positive restraint thereby.

To provide a vapor-tight joint between the ends of the top-plates 20 and the upper edges of the side-plates 21, as shown in Fig. 71 6, the upper edges of the side-plates are formed with outwardly-turned assembling-flanges 29 between which and the ends of the top-plates I place longitudinally-arranged resilient packing-strips 30. The upper ends 75 of the side-battens 27 aforesaid are provided with corresponding flanges 31 perforated for the passage of bolts 32 which also extend through the adjacent end of the top-batten 24 and between the packing-strips 30. The upper ends 80 of the vertical packing-strips 26 are bent outwardly, as at 33, so as to intervene between the flanges 29 of the side-plates 20 and the flanges 31 of the battens 27.

It will be understood that the packing-strips 30 extend throughout the length of the oven at the upper corners thereof, between the underfaces of the ends of the top-plates of the several lining-units and the outwardly-turned flanges 29 of the side-plates thereof, as shown in Fig. 2, but the top-batten 24 and the side-battens 27 are localized over the seams between the adjacent edges of the side-plates and top-plates, as shown in Fig. 2.

While there is comparatively little tendency for the vapors generated within the oven to escape at the bottom of the side-walls thereof, this is substantially prevented by locating the oven-floor 34 above the lower 100 ends of the side-plates 21 of the lining-units, as shown in Fig. 3.

After the several metal parts of the oven-structure have been assembled as above described and a relatively-long inverted U-shaped over-lining with yielding vapor-tight joints has been produced, the lining as a whole is then enclosed, top and sides, in an envelope 22 of insulating material of any desired character and thickness.

My present invention is not concerned with the loading and delivery openings of the oven-structure, which may be of any standard type.

Under my invention, as thus described, the metal lining of the oven is composed of a series of transverse lining-units yieldingly sealed together, each unit being free to expand and contract without affecting its neighbor, so that the longitudinal expansion and contraction of the metal lining of the oven is subdivided and localized, with the result that the insulating envelope is not racked nor the metal oven-lining distorted, as occurs when the oven-lining contracts and expands as one piece. I may here state that the metal lining of such an oven is usually so narrow and so low, compared with its length, that it has not been found essential to provide for the factors of lateral and

vertical expansion, though as shown in Fig. 6, the bolt-holes provided for the bolts, by which the several lining elements of the oven are secured in place, are made larger than the bolts which they are intended to receive, thus providing for a limited amount of lateral and vertical expansion and contraction.

By means of my improved oven-structure, with its elastic vapor-tight joints, distributed at intervals throughout its length, I am able to overcome the objections recited at the outset of this description and produce an oven of high thermal efficiency, providing exceptionally sanitary and agreeable working conditions for the staff operating it, securing economy in maintenance and use and also durability. My improved oven-structure is peculiarly adapted for baking bread, since the beneficial vapors thrown off thereby are retained for their effect upon the loaves. In case the oven is used for baking japanned or painted articles, it is desirable that their surfaces shall not be fouled by the accumulation upon them of the fine dust resulting from the disintegration of the insulating material. All this is perfectly guarded against by my invention.

In the modified construction shown by Figs. 7 and 8, the lining-unit plates 35, which may be either top- or side-plates, have their edges lapped and separated by two strips 36 of resilient packing material pinched between the overlapping edges of the plates by means of clamping-bolts 37 passing through enlarged holes in the plates, so as to permit relative movement thereof under contraction or expansion, while at the same time securing between them a vapor-tight joint.

I claim:

1. An externally-insulated oven having an insulation-protecting metal lining transversely divided to form lining-units, a linear series of frames spaced apart to support the adjacent edges of the said lining-units, and yielding vapor-tight joints sealing the lining-units together and comprising resilient packing- and batten-strips and also comprising means for clamping the edges of the units and resilient packing between the said frames and battens, whereby the contraction and expansion of any one unit does not affect its neighbor.

2. An externally-insulated oven having an insulation-protecting metal lining transversely divided to form lining-units, each of which consists of a top-plate and two complementary side-plates, the upper ends of which latter are bent outwardly to form assembling-flanges, a resilient packing interposed between the said flanges of the side-plates and the ends of the complementary top-plates, and yielding vapor-tight joints sealing the several units together, whereby

the contraction and expansion of any one unit does not affect its neighbor.

3. An externally-insulated oven having an insulation-protecting metal lining transversely-divided to form lining-units, yielding vapor-tight joints for sealing the said lining-units together in series, and a continuous body of heat-insulating material applied directly over the outer surfaces of the said lining-units and the said yielding vapor-tight joints, whereby the contraction and expansion of any one lining-unit does not affect its neighbor, and whereby the contraction and expansion of the lining-units take place independently of the said body of heat-insulating material.

4. An externally-insulated oven having an insulation-protecting metal lining transversely-divided to form lining-units, yielding vapor-tight joints for sealing the said lining-units together in series, a continuous body of heat-insulating material applied directly over the outer surfaces of the said lining-units and the said yielding vapor-tight joints, and a linear series of frames located within the said lining and spaced apart to support the said units, whereby the contraction and expansion of any one lining-unit does not affect its neighbor, and whereby the contraction and expansion of the lining-units take place entirely independently of the said body of heat-insulating material.

5. An externally-insulated oven having an insulation-protecting metal lining transversely-divided to form lining-units, yielding vapor-tight joints for sealing the said lining-units together in series, a continuous body of heat-insulating material applied directly over the outer surfaces of the said lining-units and the said yielding vapor-tight joints, and a linear series of frames located within the said lining and spaced apart to support the adjacent edges of the said lining-units, whereby the contraction and expansion of any one lining-unit does not affect its neighbor, and whereby the contraction and expansion of the lining-units take place independently of the said body of heat-insulating material.

6. An externally-insulated oven having an insulation-protecting metal lining, transversely-divided to form lining-units, yielding vapor-tight joints for sealing the said lining units together in series, a continuous body of heat-insulating material applied directly over the outer surfaces of the said lining-units and the said yielding vapor-tight joints, and a linear series of frames located within the said lining and spaced apart to support the adjacent edges of the said lining-units, which are clamped to the said frames at the said yielding vapor-tight joints, whereby the contraction and expansion of any one lining-unit does not affect

its neighbor, and whereby the contraction and expansion of the lining-units take place entirely independently of the said body of heat-insulating material.

3. 7. An externally-insulated oven having an insulation-protecting metal lining transversely-divided to form lining-units, each of which consists of a top-plate and complementary side-plates, a linear series of frames spaced apart to support the adjacent edges of the said lining-units, and yielding vapor-tight joints sealing the adjacent edges

of the said lining-units together and comprising resilient packing- and batten-strips and also comprising means for clamping the edges of the lining-units and resilient packing between the said frames and batten-strips, whereby the contraction and expansion of any one lining-unit does not affect its neighbor.

20 In testimony whereof, I have signed this specification.

EMERICK B. CRAWFORD.
